UNITED STATES PATENT OFFICE.

HIERONYMUS ZIELINSKI, OF BERLIN, GERMANY.

OIL-PUMP FOR MOTORS.

1,162,431.

Specification of Letters Patent. Patented Nov. 30, 1915.

Application filed December 30, 1913. Serial No. 803,469.

To all whom it may concern:

Be it known that I, HIERONYMUS ZIELINSKI, a subject of the King of Prussia, and residing at Alt Boxhagen 17/18, Berlin O, 5 112, Germany, have invented certain new and useful Improvements in Oil-Pumps for Motors, of which the following is a specification.

This invention relates to an oil pump for 10 internal combustion and other motors, the improved pump being particularly suitable for use with internal combustion motors employed on motor vehicles.

The oil pump is of the kind adapted to be 15 driven by the motor to which it is applied in such a way as to deliver oil automatically while the motor is running. The hand-operated oil pump has a disadvantage of requiring continual personal attention. The 20 sight-feed type does not deliver a uniform amount of oil, because of the rise or fall of the pressure in the casing. They furthermore consume large quantities of oil.

My improved oil pump is economical in 25 action, and delivers regulated amounts.

A further important advantage consists in the fact that owing to its small dimensions it can be fitted in places where it has been undesirable or even impossible to provide 30 an oil pump as heretofore usually constructed.

Figure 1 represents a vertical section of an embodiment of my oil pump, and Fig. 2 is a cross-section of line A—B of Fig. 1.

The pump body 2 is made in one with the cover of the casing 1 and is formed with an opening 3 which communicates with the oil reservoir and an opening 4, which is located within the casing 1 and serves for the outlet 40 of the oil. Fitted in the pump body 2 is a cylindrical member 5 which is formed with an axial hole or boring 6 to receive the pump piston 7. The cylindrical member 5 is formed with two holes 8 and 9 adapted when 45 the said member is rotated to register alternately with the openings 3 and 4 respectively. The end portion of the cylindrical member 5 extending beyond the pump body

is solid and is formed with a screw thread on which a nut 10 and a driving head 11 are 50 screwed. The driving head 11 is rotated by projections 12 formed on a worm wheel 13 driven from the cam shaft. Fitted to work endwise on the cylindrical member 5 is a sleeve 14 on the upper end of which a cap or 55 hollow nut 15 is screwed. The reduced upper end 16 of the piston 7 extends through the cap 15 and is fitted with lock-nuts above the cap. The sleeve 14 is formed with a hole 18 in which is fitted a ball that engages a 60 peripheral cam groove 19 in the member 5. A spring ring 20 prevents the ball from falling out of the hole 18. Fitted in the pump body 2, as is clearly shown in Fig. 2, is a ring 21 provided with a number of projections 25 that engage slots cut in the lower edge of the sleeve 14 to prevent the sleeve from rotating while admitting of its freely sliding up and down. When the motor is running the cylindrical member 5 is rotated 70 by the driving projections 11 and 12 and the sleeve 14 is thereby moved up and down through the ball working in the peripheral groove 19 of the said member; the sleeve 14 in turn positively moves the piston 7 through 75 the disk 22, that constitutes the top of the sleeve, in one direction and through the screwed cap 15 in the other direction. By screwing the cap 15 to a greater or lesser extent in the sleeve 14 the stroke of the piston 80 can be regulated at will, and when the cap 15 is screwed quite down, from its highest position in which it is shown in the drawing, on to the disk 22, the piston is not actuated at all. A spring 24 prevents the adjustable cap 15 from working loose. 85

What I claim is:—

1. In an oil pump for motors, a casing formed with oil inlet and outlet ports, a member adapted to revolve in said casing 90 formed with a pump chamber and inlet and outlet ports adapted to alternately register with the inlet and outlet ports of said casing as said member revolves, a pump piston arranged to reciprocate in the chamber 95 of said revolving member, a sleeve engag-

ing said piston and mounted to reciprocate on said rotary member, and means connecting said rotary member to said sleeve adapted to reciprocate said sleeve by the revolution of said member.

2. In an oil pump for motors, a casing formed with oil inlet and outlet ports, a member adapted to revolve in said casing and formed with a pump chamber and inlet 10 and outlet ports adapted to alternately register with the inlet and outlet ports of said casing as said member rotates, a pump piston arranged to reciprocate in the chamber of said rotary member, a sleeve mounted to 15 reciprocate on said rotary member, an extension projecting from said piston, a stop on said extension, a part on said sleeve engaging said extension between said piston and said stop, and means connecting said 20 revolving member to said sleeve and adapted to reciprocate said sleeve by the revolution of said member.

3. In an oil pump for motors, a casing formed with oil inlet and outlet ports, a 25 cylindrical member adapted to revolve in said casing, the said member being formed with a peripheral cam groove, with inlet and outlet ports adapted to alternately register with the inlet and outlet ports of said casing 30 as said member rotates, and with a pump chamber, a pump piston arranged to reciprocate in the chamber of said revolving member, a sleeve engaging said piston and mounted to reciprocate on said rotary member, the 35 said sleeve being formed with a hole, and a ball engaging the hole in said sleeve and the peripheral groove of said cylindrical revolving member.

4. In an oil pump for motors, a casing 40 formed with oil inlet and outlet ports, a member adapted to revolve in said casing and formed with a pump chamber and inlet and outlet ports adapted to alternately register with the inlet and outlet ports of said 45 casing as said member revolves, a pump piston arranged to reciprocate in the chamber of said revolving member, a sleeve mounted to reciprocate on said rotary member, an extension projecting from said piston, an adjustable stop on said extension, a part on said sleeve engaging said extension between said piston and said stop, and means connecting said revolving member to said sleeve and adapted to reciprocate said sleeve 55 by the revolution of said member.

5. In an oil pump for motors, a casing formed with oil inlet and outlet ports, a member adapted to revolve in said casing and formed with a pump chamber and inlet 60 and outlet ports adapted to alternately register with the inlet and outlet ports of said casing as said member revolves, a pump piston arranged to reciprocate in the chamber

of said revolving member, a sleeve mounted to reciprocate on said revolving member, an extension projecting from said piston, a stop on said extension, an adjustable cap on said sleeve engaging said extension between said piston and said stop and means connecting said revolving member to said sleeve and 65 adapted to reciprocate said sleeve by the revolution of said member.

6. In an oil pump for motors, a casing formed with oil inlet and outlet ports, a member adapted to revolve in said casing 70 and formed with a pump chamber and inlet and outlet ports adapted to alternately register with the inlet and outlet ports of said casing as said member rotates, a pump piston arranged to reciprocate in the chamber 75 of said revolving member, a sleeve provided with an external screw thread for a part of its length and mounted to reciprocate on said rotary member, an extension projecting from said piston, a stop on said extension, 80 a cap screwed on said sleeve engaging said extension between said piston and said stop, and means connecting said rotary member to said sleeve and adapted to reciprocate said sleeve by the revolution of said member. 85

7. In an oil pump for motors, a casing formed with oil inlet and outlet ports, a member adapted to revolve in said casing and formed with a pump chamber and inlet and outlet ports adapted to alternately register with the inlet and outlet ports of said casing as said member revolves, a pump piston arranged to reciprocate in the chamber of said revolving member, a sleeve provided with an external screw thread for a 90 part of its length and mounted to reciprocate on said rotary member, an extension projecting from said piston, a stop on said extension, a cap screwed on said sleeve engaging said extension between said piston and said stop, a spring within said cap, and means connecting said revolving member to said sleeve and adapted to reciprocate said sleeve by the revolution of said member. 95

8. In an oil pump for motors, a casing 110 formed with inlet and outlet ports, a cylindrical member constituting a pump chamber mounted to revolve in said casing, said member being formed with a peripheral cam groove and with inlet and exhaust ports 115 adapted to register alternately with the inlet and exhaust ports of said casing as said member rotates, a sleeve mounted to slide on said member, means for preventing revolving movement of said sliding sleeve, 120 said sleeve being formed with a hole, a ball engaging the hole in said sleeve and also the cam groove of said member, a part fixed to said sleeve engaging said piston, an extension on said piston that projects through 125 said part, a nut on said extension, a cap ad-

justable on said sleeve and engaging said extension between said nut and said part, and a spring located in said cap.

9. In an oil pump for motors having a
5 casing formed with oil inlet and outlet
ports, and a movable member having inlet
and outlet ports adapted to alternately reg-
ister with the inlet and outlet ports of said
casing, an inclosed pump chamber, a piston
10 adapted to reciprocate in said pump cham-

ber, and means whereby said movable mem-
ber is connected with said piston, to move
it, at any desired point in the movement of
said movable member.

In testimony whereof I affix my signature 15
in presence of two witnesses.

HIERONYMUS ZIELINSKI.
